Patented May 30, 1922.

UNITED STATES PATENT OFFICE

TONJES A. BOTH, OF STRATFORD, CONNECTICUT, ASSIGNOR TO THE CONNECTICUT ELECTRIC MANUFACTURING COMPANY, A CORPORATION OF CONNECTICUT.

RENEWABLE CARTRIDGE FUSE.

1,417,966.

Specification of Letters Patent. Patented May 30, 1922.

Application filed July 18, 1918. Serial No. 245,550.

To all whom it may concern:

Be it known that I, TONJES A. BOTH, a citizen of the United States, residing at Stratford, county of Fairfield, State of Connecticut, have invented an Improvement in Renewable Cartridge Fuses, of which the following is a specification.

This invention relates to renewable cartridge fuses of both the ferrule and blade types and has for its object to provide a fuse ventilated at the ends and provided with refractory heads so as to prevent injury to a marble switch base in the event of the blow out, to prevent arcing, to prevent fusing of any of the movable parts and to prevent the substitution of wire for a fuse strip in the event of a blow out. A further object of the invention is to provide a fuse strip having stops so located with relation to the heads as to properly locate the indications on the strip with relation to the holes in the ferrules.

With these and other objects in view, I have devised the renewable fuse which I will now describe referring to the accompanying drawing forming a part of this specification and using reference characters to indicate the several parts.

Figure 1 is a side elevation of one of my novel fuses of the ferrule type;

Figure 2 an end elevation corresponding therewith;

Figure 3 a section on the line 3—3 in Figure 4;

Figure 4 a longitudinal section of a fuse of the ferrule type;

Figure 5 a perspective view of one of the refractory heads, detached;

Figure 6 a perspective view of the fuse strip, detached;

Figure 7 a perspective view of one end of a fuse of the ferrule type, showing the parts disassembled;

Figure 8 a side elevation of one end of a fuse of the blade type;

Figure 8^a a longitudinal section of the other end of the fuse, which has been given a quarter turn;

Figure 9 an end elevation partly broken away, as seen from the right in Figure 8^a;

Figure 10 a similar view illustrating a variant form of blade, and

Figure 11 is a section on the line 11—11 in Figure 10.

20 denotes the body which is ordinarily a fibre tube, and is externally threaded at its ends for engagement by internal threads on the ferrules 21. The ends of the body are closed by heads 22 which are made of refractory or relatively non-fusible material, being preferably moulded from vitreous 60 material, as porcelain or glass. Bakelite can be used if preferred, or even a high grade of compressed fibre. I preferably, however, use vitreous material as it cannot be drilled and consequently prevents the substitution of wire for a fuse strip in the event of a blow out. 23 denotes the fuse strip which is preferably made narrowest at its midlength so that fusing will take place midway between the heads, and is provided with 70 indications 24 which show the safety amperage of the fuse and with stops 25, which are shown as formed by displacing metal of the strip laterally, and are so located with relation to the heads as to prevent longitudinal movement and fix the indications, when assembled, in alignment with holes 26 in the ferrules, which in this form may be placed centrally. The heads are provided with slots 27, ordinarily placed at one side of the 80 center, with shoulders 28 adapted to rest on the ends of the body, with lugs 29 adapted to engage notches 30 in the ends of the body to lock the heads and body against relative 85 rotary movement, and in their edges with one or more ventilating channels 31 which permit the gases generated by a blow out to pass through without danger of bursting the body or blowing off the head.

In assembling, one end of the fuse strip 90 is passed through the slot in a head, the corresponding stop is drawn against the inner side of the head and the end of the fuse strip is bent over the outer side of the head, as in Figure 7, leaving the indication 95 visible. The head is then inserted in the body with the lugs on the head in engagement with the notches in the body, and the

ferrule is turned to place. Then the other end of the fuse is passed through the slot in the other head, the stop is drawn against the inner side of the head and the head is seated 5 in the end of the body as before, except that the head is given a half turn so as to place the slot on the opposite side of the body which causes the fuse strip to pass obliquely through the body. Then the end of the fuse 10 strip is bent over the outer side of the head as before and the ferrule is turned to place. It will be noted that the thickness of the fuse strip, which is clamped between the head and the ferrule, at each end, leaves the 15 head and the ferrule separated and provides a gas chamber, indicated by 32. From this chamber, in the event of a blow out, the gas can pass out freely through holes 33 in the end of the ferrule.

20 In devising my present construction care has been taken to avoid serious objections to fuses now upon the market. The effective end ventilation prevents injury to a marble base and prevents either bursting of the body or 25 blowing off of a head in the event of a blow out, and the non-use of metallic parts with the exception of the ferrules, which are effectively insulated by the body and the heads, does away with all danger or arcing, 30 and with all danger of the fusing of metallic connecting parts which has heretobefore rendered many so called renewable fuses useless after a blow out.

It is of course well understood that the 35 smaller sizes of fuses, that is fuses for 60 amperes and under, are ordinarily of the ferrule type and fuses for 100 amperes and upward are of the blade type. In Figures 40 8 to 11 inclusive I have illustrated forms of renewable fuses of the blade type, the difference being that in the latter type the circuit is through the blades which are in 45 electrical contact with the fuse strip.

In Figures 8^a and 9, 34 denotes the blade 50 which is formed from a piece of sheet metal tubing flattened to place the sides in parallelism but not in contact. The object being to leave a longitudinal passage 35 between the sides of the flattened tube for the escape of 55 gas through the blade itself from chamber 32 in the event of a blow out. The inner end of the blade is provided with a base 36 which is formed by splitting the flattened tube and bending the sides outward at right angles 60 to the blade. The base is provided at one side of the blade with a hole 37 through which the indication is visible. In this form the heads are provided on the outer side at the edges with notches 38 which are engaged 65 by lugs 39 on the bases. These lugs and notches lock the blades against rotary movement relatively to the heads and insure that

the holes 37 will always be in alinement with the indications. The ferrules in this form, indicated by 40, are provided with relatively 65 large holes 41 through which the blades extend and the indications are visible.

The form illustrated in Figures 10 and 11 differs in that the blade, indicated by 42, is formed from a flat bar or strip of metal 70 which is split at its inner end and the base 43 is formed by bending the sides outward at right angles to the blade as before. The ventilation in this form is through holes 44 in the base. The notches 38 and lugs 39 are 75 the same as in the other form.

Having thus described my invention, I claim:

1. In a fuse of the character described an insulating tubular body, removable refractory heads closing the ends of the body and provided with slots and in their edges with ventilating channels, a fuse strip passing through the slots and having its ends bent over the outer sides of the heads, and ferrules having holes in their ends and threaded engagement with the body. 80

2. In a fuse of the character described an insulating tubular body having notches in its ends, removable refractory heads having 90 shoulders engaging the ends of the body, and provided with slots, lugs engaging the notches, a fuse strip passing through the slots and having its ends bent over the outer sides of the heads, and ferrules engaging 95 the body.

3. In a fuse of the character described a body, removable refractory heads closing the ends of the body and provided in their edges with ventilating channels, a fuse strip passing through the heads and having its ends bent over the outer sides of the heads, ferrules engaging the body and leaving chambers between the heads and the ferrules, and means for permitting escape of gas from the 105 chambers. 100

4. In a fuse an insulating tubular body, refractory heads having ventilating channels, a fuse strip passing through the heads, ventilating blades having bases contacting 110 with the fuse, and ferrules engaging the body.

5. In a fuse an insulating tubular body, refractory heads having ventilating channels, a fuse strip passing through the heads, 115 ventilating blades comprising flat metal tubes having the side walls at their inner ends bent outwardly in opposite directions, and ferrules engaging the body by which the parts are retained in place. 120

6. In a fuse an insulating body, a fuse strip, blades having a ventilating passage extending longitudinally therethrough, and means for connecting the blades to the body.

7. A ventilating fuse blade comprising a flat metal tube with the sides of the inner end of the tube bent outwardly in opposite directions to form a base.
- 5 8. A blade for a cartridge fuse having a ventilating passage extending longitudinally therethrough.
9. A head for renewable cartridge fuses made of refractory material and provided with a fuse slot, and with one or more ventilating channels in its edge.

10. A head for renewable cartridge fuses made of refractory material and provided with shoulders, with a lug, with a fuse slot, and with one or more ventilating channels 15 in its edge.

In testimony whereof I affix my signature.
TONJES A. BOTH.
